SPOOL OR BOBBIN

George B. Markle, Jr., Hazleton, Pa., assignor to
 Freeland Spool & Bobbin Corp., Hazleton, Pa.,
 a corporation of Pennsylvania

Application March 4, 1946, Serial No. 651,899

4 Claims. (Cl. 242—46.3)

1

This invention pertains to spools or bobbins but more particularly and specifically to a novel and improved construction to facilitate, simplify and improve the manner of driving, that is rotating, spools or bobbins.

The primary object of the invention is accordingly the provision of a spool or bobbin constructed in a manner whereby it can be driven in a novel and improved manner.

By reason of the construction provided for the drive of the spool or bobbin other advantages are obtained, the nature of which will be set forth in the following detailed description of the invention.

One embodiment of the inventive concept is illustrated in the accompanying drawings but departures from the specific construction illustrated therein can be made without departure from the inventive concept, and the drawings are accordingly to be considered as illustrative and not limitative of the invention as the invention is to be limited only within the scope of the hereinafter following and appended claims.

In the drawings:

Figure 1 is a longitudinal sectional view through a spool or bobbin embodying the inventive concept.

Figure 2 is an end view of an adapter suitable for driving the spool or bobbin.

Figure 3 is a longitudinal sectional view through the adapter illustrated in Figure 2.

Figure 4 is an end view of the spool or bobbin with the adapter therein, a portion of the view being broken away and the spindle being shown in section to better illustrate the invention.

Referring now to the drawings and describing in detail the construction illustrated thereby, A is a hollow thin walled open ended barrel the length of which is optional, but in the present instance is approximately nine inches long. Internally the barrel is provided with integral longitudinally extending spaced ribs 1, 2 and 3. The thickness, depth, and precise configuration of these ribs is optional as is likewise the number of ribs provided around the interior diameter of the barrel. It is thought that three ribs are fully adequate but a greater number could be provided were it found desirable for any reason.

The spool or bobbin is completed by the provision of a head at each end of the barrel and the particular construction of these heads could and will vary in accordance with the particular use for which the bobbin is intended.

In the bobbin embodiment here illustrated there is at one end of the barrel a head B and at

2

the opposite end of the barrel a second head C which for clarity in description in differentiating it from the head B will be referred to as a knob. The head B at its under side is centrally recessed at 4 to receive the reduced end 5 of the barrel, which construction provides on the barrel a shoulder 6 against which the under side of the head abuts. The head is provided with a central opening which telescopically receives a ring D which at its outer end is provided with a circumferential flange 7 abutting and lying against the outer face of the head and is provided with an inwardly extending skirt 8. This skirt extends into the interior of the barrel and to accommodate it the barrel ribs at this end of the barrel stop short of the barrel end, as clearly appears in Figure 1 of the drawings. The ring D and the head B are secured together and are in turn detachably connected to the barrel end by a plurality of screws 9 which pass into and have threaded engagement in the ends of the barrel ribs.

The knob C at the opposite end of the barrel is secured to the barrel by a plurality of screws 10 or the like which have threaded engagement with the opposite ends of the barrel ribs. This knob is provided with a central opening 11 and clamps between itself and the barrel end an insert or bearing E the interior diameter of which provides a bearing contact with a driving spindle 30 G.

The adapter F is a hollow tubular member having at its outer end a head 12 of greater diameter than the rest of the adapter so as to provide at the under side of the head a circumferential shoulder 13. Externally the adapter is provided with three cut-out portions 14, 15 and 16 which construction provides on the outer face of the adapter three ribs 17, 18 and 19. The cut out portions are for the reception of the ribs 1, 2 and 3 of the bobbin barrel while the ribs 17, 18 and 19 are intended to be disposed in the spaces between the barrel ribs.

It will be understood that the adapter has suitable driving connection with a spindle or shaft G from which it receives rotative motion.

The manner of use and operation of the arrangement is as follows. The diameter of the opening in the ring D is such as to snugly receive the head 12 of the adapter. The adapter is slid 50 through the ring opening until the shoulder F of the adapter abuts the ends 20 of the barrel ribs. The cut out portions 14, 15 and 16 of the adapter receive the ribs 1, 2 and 3 of the barrel and the ribs 17, 18 and 19 of the adapter are disposed in the spaces between the barrel ribs. This

is most clearly illustrated in Figure 4 of the drawings. In the particular arrangement illustrated the cut-out portions of the adapter are shown of greater width than that of the barrel ribs but such an arrangement is not essential as a snug fit between the ribs of the barrel and the cut-out portions of the adapter could be provided. From the foregoing description it will be seen that upon rotation of the spindle or shaft G this rotative motion will be imparted to the adapter which in turn through the ribs of the barrel will rotate the bobbin.

The arrangement provides a simple yet highly efficient drive for a spool or bobbin. Ordinarily spools or bobbins are driven by providing a driving connection between one of the spool heads and the driving spindle or shaft. This has decided disadvantages one of which is that all of the strain is put upon the head which necessitates a very strong connection between the head and barrel of the bobbin which in turn necessitates that the barrel be of a thick wall construction. In the present arrangement the driving torque or strain is imparted to the barrel ribs and by them is distributed throughout the full length of the barrel. As a consequence of this arrangement the barrel walls may be thin and the thickness necessary to securing the barrel heads in place is provided by the ribs. Additionally, because of lack of torque or strain upon them no exceptionally rigid connection between the barrel and its heads is necessary. One of the weaknesses and drawbacks of prior constructions and practices was the necessity of a very rigid connection between the bobbin head and barrel due to the fact that the drive of the bobbin was imparted through the bobbin head. This prior practice has necessitated the provision of many different constructional arrangements to assure the necessary rigid connection of the bobbin head to the barrel.

Additionally the present arrangement makes it possible to use light metals in the spindle barrel and this makes it possible to form the barrel ribs by extrusion. In fact, the arrangement is such that the barrel may be made of plastic or any other suitable material which can be easily and simply extruded or otherwise in a simple manner given the desired form and shape. Obviously the bobbin heads, like the barrel, can be made of plastics, or light metal, or any suitable material, by reason of the fact that they are not subjected to the stresses and strains to which they have been heretofore subjected in bobbins as driven in the conventional and usual manner heretofore practiced as hereinbefore described.

Conditions and the particular uses to which the bobbin is to be put may require barrel ribs in different numbers and different configuration than that illustrated in the drawings and obviously such variations can be simply accommodated and when provided necessitate only that the adapter cut-out portions be altered to cooperate with changes made in the bobbin barrel ribs. Although it is the more desirable construction it is not essential that the ribs extend throughout the length of the bobbin barrel. Variables in rib lengths can be made to meet the particular conditions just as the overall length of the adapter is optional to meet any specific condition or use.

The inventive concept and the mode of operation of the invention being clear from the foregoing description when read in the light of the

accompanying drawings the invention is defined as follows.

I claim:

1. In a spool, bobbin or the like, a hollow open-ended barrel provided interiorly with longitudinally extending spaced ribs extending substantially throughout the length of the barrel, a head at each end of the barrel and each provided centrally with an aperture, a tubular hollow bearing disposed and supported within one end of the barrel, the aperture of the head at the opposite end of the barrel provided with a bearing ring, a hollow adapter disposed wholly within the barrel and said ring and provided exteriorly with spaced longitudinally extending grooves interlocking with the ribs of the barrel, a drive spindle having driving connection with said adapter and extending therethrough, the outer end of said spindle being rotatably supported in the tubular bearing in the opposite end of the barrel.
2. In a spool, bobbin or the like, a hollow open-ended barrel provided interiorly with spaced longitudinally extending ribs stopping short of one end of the barrel to provide shoulders, heads at the opposite ends of the barrel and each provided centrally with a passageway, a tubular hollow bearing disposed within one end of the barrel and held in position by being clamped between the end of the barrel and one of the heads, a hollow adapter rotatably supported within the passageway of the head at the opposite end of the barrel and having a shoulder in abutment with the shoulders of said ribs, the interior bore of said adapter being in alignment with the bore of said bearing, said adapter exteriorly provided with a plurality of spaced longitudinally extending grooves adapted to receive the ribs of said barrel, a drive spindle extending through the adapter and having driving connection therewith, and the end of said spindle being rotatably supported in said bearing.
3. In a spool, bobbin or the like, a hollow-open-ended barrel provided interiorly with longitudinally extending spaced ribs, said ribs extending from one end of the barrel to a point closely adjacent but short of the other end of the barrel to provide shoulders, a centrally apertured head detachably secured to each end of the barrel, a tubular hollow bearing provided at one end with a circumferential outwardly extending flange, said bearing being disposed in one end of the barrel and having its flange clamped between the ends of the barrel ribs and one of said detachable heads, the aperture of the other barrel head provided with a ring having an inwardly extending skirt forming a bearing, an adapter provided with a head having a diameter to closely rotatably fit said ring skirt, said adapter being hollow and disposed wholly within said head and barrel and provided exteriorly with a plurality of spaced grooves interlocking with the ribs of the barrel, said adapter having a shoulder abutting the shouldered ends of the ribs to limit the movement of the adapter into the barrel, a drive spindle having driving connection with said adapter and extending therethrough whereby said adapter acts as a support for the spindle, and the end of the spindle being rotatably supported in the bearing in the opposite end of the barrel.
4. In a spool, bobbin or the like, a hollow open-ended barrel provided interiorly with spaced longitudinally extending ribs, a head at each end of the barrel, a driving spindle extending through an aperture provided in one head and having its end rotatably supported in a bearing disposed

interiorly of the other end of the barrel, a short tubular adapter having driving connection with the spindle and disposed within the barrel, said adapter exteriorly provided with a plurality of spaced longitudinally extending grooves adapted to interlock with the ribs of the barrel, said adapter having a portion abutting one end of the barrel ribs to limit the inward movement of the adapter, and said adapter being rotatably supported in the aperture of the barrel head.
